(57) **CLAIM**

The ornamental design for a lint card package, as shown and described.

DESCRIPTION

FIG. 1 is a perspective view of a lint card package showing our new design, shown in an open position;

FIG. 2 is a perspective view of the lint card package;

FIG. 3 is a top view of the lint card package of FIG. 2;

FIG. 4 is a bottom view of the lint card package of FIG. 2;

FIG. 5 is a front view of the lint card package of FIG. 2;

FIG. 6 is a rear view of the lint card package of FIG. 2; and,

FIG. 7 is a right side view of the lint card package of FIG. 2, the left side view being a mirror image thereof.

The surface shading illustrated in the drawings is provided merely to highlight the contour design; it is not intended to be illustrative of texture or gloss and forms no part of the claimed design.
